(57) **CLAIM**

The ornamental design for a nerve model set, as shown and described.

DESCRIPTION

FIG. 1 is a perspective view of a nerve model set showing the new design;

FIG. 2 is an exploded front elevation view without environment;

FIG. 3 is an exploded rear elevation thereof;

FIG. 4 is an exploded right-side elevation view thereof;

FIG. 5 is an exploded left-side elevation view thereof;

FIG. 6 is an exploded top plan view thereof; and,

FIG. 7 is an exploded bottom plan view thereof.

The broken lines depicting a stand in FIG. 1 are included for the purpose of illustrating environmental structure and form no part of the claimed design.
